UNITED STATES PATENT OFFICE

90,754

DESIGN FOR SHEET MATERIAL

Walter Ebling, New York, N. Y.

Application July 18, 1933. Serial No. 48,754

Term of patent 3½ years

To all whom it may concern:

Be it known that I, WALTER EBLING, a citizen of the United States, residing at 556 Madison Ave., New York, in the county of New York and State of New York, have invented a new, original, and ornamental Design for Sheet Material, of which the following is a specification, reference being had to the accompanying drawing, forming part thereof.

The single figure is a plan view of the design. The design is applicable to all kinds of sheet

material and particularly to paper. Naturally sheet material having this ornamental design may be used for the backs of playing cards, book covers, lamp shades, and a great variety of objects, in which cases it may either constitute the article itself or may be pasted thereon, as in the case of a lamp shade.

I claim:

The ornamental design for sheet material substantially as shown and described.

WALTER EBLING.
